UNITED STATES PATENT OFFICE.

JULIO E. CORDOVEZ, OF PANAMA, COLOMBIA.

COIN-CONTROLLED TELEPHONE.

SPECIFICATION forming part of Letters Patent No. 669,875, dated March 12, 1901.

Application filed August 16, 1900. Serial No. 27,041. (No model.)

To all whom it may concern:

Be it known that I, JULIO E. CORDOVEZ, a citizen of the United States of Colombia, (at present known as the Republic of Colombia,) 5 and a resident of Panama, in the Republic of Colombia, have invented a new and Improved Coin-Controlled Telephone, of which the following is a full, clear, and exact description.

The object of my invention is to produce a 10 simple telephonic apparatus in which the introduction of a coin of predetermined value is necessary in order to close the speaking-circuit.

The invention will be fully described hereinafter and its novel features pointed out in the appended claims.

Reference is to be had to the accompanying drawings, forming a part of this specification, in which similar characters of reference indicate corresponding parts in all the figures.

Figure 1 is an exterior perspective view of the apparatus. Fig. 2 is a partial vertical section through the receiver-support, showing it in connection with the coin-chute. Fig. 3 is 25 a side view, looking from the right-hand end of Fig. 2, with part of the coin-chute and of the circuit-closer in section; and Fig. 4 is a perspective view of the apparatus with the lid open and parts of the front removed to dis- 30 close the interior construction.

The apparatus comprises a suitable casing A, preferably divided into three compartments by horizontal partitions A' A². In the lowermost compartment B is located the battery C. The next compartment B' contains the coin-receptacle D, located under an aperture A³ of the partition A². The upper compartment B² holds the main parts of the apparatus. These consist, first, of a magneto- 35 electric machine E of any approved construction, with the call-bell F in operative relation thereto, as usual. From one terminal E' of the magneto a wire G leads to a contact G', adapted to engage a spring H on the hinged 40 lid A⁴ when said lid is closed. A wire G² connects the other terminal E² of the magneto with the electromagnets of the call-bell, from which another wire G³ leads to one of the 45 hinges A⁵, also connected by a wire G⁴ with a terminal G⁵, connected with the earth or with a line to another station. From the wire G³ a wire G⁶ leads to a binding-post G⁷, connect-

ed by a wire G⁸ with one terminal of the receiver I, which may be of any approved construction. The other terminal of the receiver 55 is connected by a wire G⁹ with a binding-post G⁰. This post is connected by a wire J' with the secondary winding of the induction-coil J. The other end of the secondary winding is connected by a wire J² with a resilient contact-arm H', secured to the lid A⁴.

The receiver I normally rests upon a dished supporting-plate K, having a stem K', which passes through a recess A⁶ in the lid A⁴, the stem being under the influence of a coiled 65 spring L, which raises the support when the receiver is removed therefrom. The stem K' carries a conducting cross-plate K², movable between the contact-arms H H' and adapted to engage only one of them at a time. When 70 the support K is depressed, as shown in Fig. 2, the plate K² engages the arm H'. Said plate also permanently engages a further contact-arm H², connected by a wire J³, and through the medium of one of the hinges A⁵ 75 with a wire J⁴, leading to the binding-post J⁵, connected with the line.

With the stem K' moves a lever M, the latter having, for instance, an aperture to receive said stem and being held between the 80 plate K² and a nut K³. This lever is fulcrumed at M' upon an arm M², extending from the coin-chute N, and preferably is in electrical connection therewith, although this is not necessary. The coin-chute has an orifice 85 N' for the insertion of the coin and has an inclined curved bottom N², which terminates short of the inner end of the chute. The coin after rolling off said bottom N² rests upon a pivoted coin-support O, fulcrumed at O' to 90 the coin-chute and in electrical connection therewith. The other end of the support O is of sufficient weight (or it might be spring-pressed) to keep the coin-receiving end of the support up as long as no coin rests thereon. 95 This coin-receiving end is made with upward flanges or is U-shaped. (See Fig. 2.) The lower end of the coin-chute is open, so that the coin could escape therefrom were it not for the fact that at the time the coin is introduced the outlet of the coin-chute is partially blocked by a projection M³ on the retaining-lever M. This is the case at the time the receiver I is off the support K, so that the spring 100

L moves said support into its upper position. The end of the coin-chute is approximately above the opening A³.

When depressed by a coin, the coin-support O comes in contact at its weighted end with a screw P, insulated from the coin-chute and connected by a wire J⁶ with one of the hinges A⁵ and with a wire J⁷, leading from one pole of the battery C. The other pole of the battery is connected by a wire J⁸ with another of the hinges and by a wire J⁹ with one terminal of any suitable microphone or transmitter Q, the other terminal of which connects by a wire J⁰ with the primary winding of the induction-coil J, which winding at its opposite end is connected by a wire J^X with the contact-spring H'. Q', Fig. 1, is the mouthpiece of the transmitter.

While the coin-support O has a permanent electrical connection with the contact-plate K² through the medium of the retaining-lever M and of the coin-chute N, I prefer for safety's sake to provide an additional connection operative when the receiver I is taken off its support K. This connection is made by a spring-contact H³, connected with the coin-chute by a wire H⁴.

The operation is as follows: A person desiring telephonic communication will (without removing the receiver I from its support) first turn the crank E³, which operates the magneto E. This will ring the bell F at the calling-station and at the central as well, the circuit being as follows: from ground connection G⁵, through wire G⁴, hinge A⁵, wire G³, coils of bell F, wire G², magneto E, wire G, contact G', spring H', contact-plate K², spring H², wire J⁸, hinge A⁵, wire J⁴, and binding-post J⁵, to the line and central. Then the person should remove the receiver I from its support K, so that the contact-plate K² will engage the springs H' H³ while remaining in contact with the spring H², but coming out of contact with the spring H. At the same time the lever M is swung on its fulcrum M', so that the lug M² projects across the outlet of the coin-chute N. Then a coin of proper denomination is deposited in the slot N', (which is made of proper width and length to prevent the entrance of coins that are too large or too thick,) and this coin rolls on the bottom N² and on the coin-support O. If the coin is too small, it will pass under the lug M² without closing the circuit. If, however, the coin is of the right dimensions, it will be arrested by the lug M², as shown in Fig. 3, and then the weight of the coin will tilt the support O upon its fulcrum O', bringing the lever in contact with the screw P. Should the coin be too light, it will not be able to establish the contact. Assuming the contact has been made as described, the local or primary speaking-circuit is closed as follows: from the battery C by wires J⁸ and J⁹ to the transmitter Q, wire J⁰, primary winding of coil J, wire J^X, spring H', contact-plate K², spring H³, wire H⁴, and coin-chute N, (also

from plate K² to lever M and coin-chute N,) coin-support O, screw P, wires J⁶ and J⁷ to other pole of battery. The secondary or line speaking-circuit is as follows: ground connection G⁵, wires G⁴ G⁶, binding-post G⁷, receiver I, binding-post G⁰, wire J', secondary winding of coil J, wire J², spring H', contact-plate K², spring H², wires J³ and J⁴, binding-post J⁵, and line to central station. The operator at the central station then makes the desired connection in the usual manner, and the two persons can communicate with each other. When the conversation is ended, the receiver I is put back on its support K, causing the lever M to swing back into the position shown in Fig. 2 and releasing the coin, which passes through the aperture A³ into the collecting-box D.

In the apparatus of the called subscriber the parts occupy the same position as described with reference to the calling-subscriber's apparatus, with the exception of the coin-support O, which not being weighted by a coin remains in the position shown in Fig. 3. It is of course understood that the called subscriber removes his receiver I from its support. At the apparatus of the called subscriber the telephonic message therefore passes through the following circuit: from the line to binding-post J⁵, wires J⁴ J⁸, spring H², contact-plate K², spring H', wire J², secondary winding of induction-coil J, wire J', binding-post G⁰, receiver I, binding-post G⁷, and wires G⁶ G⁴ to the ground at G⁵.

It will be understood from the foregoing description that the spring H³ and wire H⁴ may be dispensed with, the lever M alone being relied upon for conveying the current from the plate K² to the coin-chute N. On the other hand, the connection might be made exclusively by means of the spring H³ and wire H⁴, the lever M in this case not requiring to be of conducting material. It will be further understood that while I have utilized the hinges A⁵ to carry the current such construction is not essential.

Having thus described my invention, I claim as new and desire to secure by Letters Patent—

1. In a telephone apparatus, the combination of the receiver, a support therefor which automatically changes its position according as the receiver rests thereon or not, a movable coin-support, a circuit adapted to be closed by the movement of the coin-support, and a movable coin-retainer operatively connected with the receiver-support and arranged to keep the coin upon the coin-support, and to release the coin when the receiver is put back on its support.

2. In a telephone apparatus, the combination of the receiver, a support therefor which automatically changes its position according as the receiver rests thereon or not, a coin-chute, a movable coin-support at the outlet end of the said chute, a circuit adapted to be closed by the movement of the coin-support,

and a coin-retaining lever mounted to swing into the path of the coin at the outlet of the chute, and operatively connected with the receiver-support.

5 3. In a telephone apparatus, the combination of the receiver, a support therefor which automatically changes its position according as the receiver rests thereon or not, a permanent connection from said support to the line, a contact arranged to be engaged by said support only when the receiver is upon the support, a call-bell circuit of which said contact forms a part, a primary induction-winding, a transmitter, and a source of electricity connected in series, a contact permanently connected with one end of the said primary winding and adapted to be engaged by the support when the receiver is taken off, a secondary induction-winding one end 15 of which is connected with the same contact as the primary winding, and the other end with the receiver, a coin-chute, a movable coin-support at the outlet of the chute, a contact connected with the coin-support and arranged to be engaged by the receiver-support when the receiver is taken off, a contact arranged to be engaged by the coin-support when the latter is weighted by a coin, a connection from the last-named contact to said 20 source of electricity, and a coin-retaining lever arranged to move with the receiver-support and to arrest a coin at the outlet of the coin-chute.

4. In a telephone apparatus, the combina-

tion of the receiver, a support therefor which 35 automatically changes its position according as the receiver rests thereon or not, a permanent connection from said support to the line, a contact arranged to be engaged by said support only when the receiver is upon the 40 support, a call-bell circuit of which said contact forms a part, a primary induction-winding, a transmitter, and a source of electricity connected in series, a contact permanently connected with one end of the said primary 45 winding and adapted to be engaged by the support when the receiver is taken off, a secondary induction-winding one end of which is connected with the same contact as the primary winding, and the other end with the receiver, a coin-chute, a movable coin-support at the outlet of the chute, a conducting connection from said coin-support to the receiver-support, a contact connected with said source of electricity and arranged to be engaged by the coin-support when the latter is weighted by a coin, and a coin-retaining lever arranged to move with the receiver-support and to arrest a coin at the outlet of the 50 coin-chute.

In testimony whereof I have signed my name to this specification in the presence of two subscribing witnesses.

JULIO E. CORDOVEZ.
